Inventor,
Joseph N. Treadwell

UNITED STATES PATENT OFFICE.

JOSEPH N. TREADWELL, OF READING, CONNECTICUT.

MACHINE FOR SCOURING AND HULLING GRAIN.

Specification of Letters Patent No. 23,127, dated March 1, 1859.

To all whom it may concern:

Be it known that I, JOSEPH N. TREADWELL, of Reading, in the county of Fairfield and State of Connecticut, have invented a certain 5 new and useful Improvement in Scouring and Hulling Grains of Any Kind; and I do hereby declare the following to be a full, clear, and exact description of the same, reference being had to the accompanying drawings, making a part of this specification, in 10 which—

Figure 1 represents a vertical section through the scouring and hulling mill. Fig. 2 represents a perspective view of the runner and its spindle, showing the grooves and rasp upon its face. Fig. 3 represents a perspective view of the same runner and spindle, turned over to show the grooves on its under or lower face. Fig. 4 represents in 15 perspective the bed, or stationary stone or disk, turned over, to show the grooves and rasp on its working face.

Similar letters of reference where they occur in the separate figures, denote like 20 parts in all the drawings.

The nature of my invention consists in providing the working faces, of a bed and runner, with grooves throughout a portion of their surfaces, and skirted with rasps, as 25 will be explained.

To enable others skilled in the art to make and use my invention, I will proceed to describe the same with reference to the drawings.

30 A, represents a stout substantial frame, upon which is arranged the curb B.

C, is a bridge-tree upon which a step a, is placed to support the lower end of the spindle D, the upper end of said spindle being supported in a suitable box or bearing b, 35 in the top bridge-tree, or frame piece E. Upon this spindle D, is affixed the runner F, so as to run within, and near the bottom of, the curb B.

40 The runner (as well as the bed G), may be made of iron, stone, or parts of each, or of any other material of which mill stones are ordinarily made, due regard being had to the special work to be done by them.

The face of the runner F, is provided with 50 grooves c, radially arranged, the outer ends d, of said grooves being closed. The skirt of the runner, outside of these grooves, is furnished with an iron or steel rings, or segments of rings, H, having a roughened or rasped surface, which surface should be slightly below the surface of the grooved portion, and this ring or rasp, may be made adjustable, so as to fit it to the surface of the stone should it become worn. It should 55 also be removable for repair. The object of the grooves is to scour, and the rasps to hull, or finish the operation.

The bed stone G (Fig. 4) is furnished with 60 concentric grooves e, on its inner portion, and a rasp I, on its skirt, like that H, of the runner, in all its essential properties.

The grain to be operated upon is fed in at 65 the eye f, and as it is slowly carried toward the skirt of the runner, is scoured and hulled, and dropping off or over said skirt falls into the curb B. There is an opening i, through 70 the curb, and the bottom of the runner F, may be furnished with radial or eccentric grooves or wings, to move the material 75 around to the delivery i.

It is obvious that either stone may be the runner without affecting the principle of the operation, and should the runner require balancing, holes or recesses n, may be left in 80 them, into which lead or any other heavy material may be put, to effect that object. Rice, buckwheat, or any other grain, may be thus treated.

Having thus fully described the nature 85 and object of my invention what I claim therein as new and desire to secure by Letters Patent is—

In combination with a bed stone and runner for scouring and hulling grain, the 90 grooves c, e, and rasping plates H, I, skirting said grooves, said parts being arranged, and operating together substantially as, and for the purpose, herein set forth.

JOSEPH N. TREADWELL.
